DESIGN FOR A HEARING AID TRANSMITTER

Frederick M. Breen, New York, N. Y., assignor to
Dictograph Products Company, Inc., New York,
N. Y., a corporation of Delaware

Application May 26, 1937, Serial No. 69,559

Term of patent 7 years

To all whom it may concern:

Be it known that I, Frederick M. Breen, a citizen of the United States, residing in the city, county, and State of New York, have invented a new, original, and ornamental Design for Hearing Aid Transmitter, of which the following is a specification, reference being had to the accompanying drawing, forming a part thereof, in which:

Figure 1 is a front elevation of a hearing aid transmitter, showing the new design; and
Fig. 2 is an edge view thereof.

The rear of the transmitter embodying the new design is substantially plain in appearance.

I claim:

The ornamental design for a hearing aid transmitter, as shown and described.

FREDERICK M. BREEN.
